UNITED STATES PATENT OFFICE.

JAMES A. PETERMAN, OF FRANKLIN, LOUISIANA.

MACHINE FOR LOWERING LUMBER.

1,172,042.

Specification of Letters Patent. Patented Feb. 15, 1916.

Application filed March 29, 1915. Serial No. 17,713.

To all whom it may concern:

Be it known that I, JAMES A. PETERMAN, a citizen of the United States, and a resident of Franklin, in the parish of St. Mary and State of Louisiana, have invented a certain new and useful Improvement in Machines for Lowering Lumber, of which the following is a specification.

This invention relates to an improvement 10 in machines for lowering lumber or other material from the tops of stacks or piles of the same.

One of the principal objects of the invention is to provide a portable machine 15 which may be moved from one place to another in a lumber yard, and which is particularly adapted for use in lowering the lumber from the tops of stacks.

Another object of the invention is to 20 provide a machine of the class described which operates through the action of gravity while lowering the lumber, and which is at all times under the control of the operator.

Still another object is to provide a machine of the type disclosed including a framework carrying an endless conveyer which is controlled by brakes, and which is provided with arms upon which the lumber may be placed in lowering the same, so 30 the frame being mounted upon a truck, so that the device can be moved from place to place in a lumber yard.

A still further object is to provide a machine for lowering lumber, including a conveyer which is disposed in an inclined plane, the upper end of which may be arranged adjacent the pile of lumber to be lowered, while the lower end of the plane 40 in which the conveyer lies, will be disposed in spaced relation to the pile of lumber, so that no interference with the work of removing the lumber from the conveyer, will be experienced.

Still another object is to provide a device 45 of the class described which will be extremely simple, durable, efficient in operation, and inexpensive to manufacture.

With these and other objects in view 50 which will become apparent as the description proceeds, the invention resides in the construction, combination, and arrangement of parts hereinafter more fully described and claimed, and illustrated in the accompanying drawings in which like characters of

reference indicate like parts throughout the several figures, of which—

Figure 1 represents a view in elevation of a machine constructed according to my invention. Fig. 2 represents a view in elevation 60 of the machine, looking toward the same from one edge or end thereof. Fig. 3 represents a view in perspective of the brake and controlling mechanism. Fig. 4 represents a view in perspective of a portion of one 65 of the conveyer chains.

In carrying out my invention I provide a platform A, on which a superstructure B is built, said superstructure including the spaced, vertically extending beams 5 which 70 arise from the platform A. A transversely extending axle 6 is carried by the superstructure above the platform A, and intermediate the ends of said platform, and on this axle are journaled the ground wheels 75 7. Smaller wheels 8 are swiveled beneath platform A adjacent the ends thereof.

The vertical beams or masts 5 extend upwardly from one side of platform A, and are connected together by suitable ties indicated at 9. The latter are braced as at 10 to the masts or beams 5. Brace beams 11 are connected at their upper ends to the vertical beams 5 near the central portion thereof, and at their lower ends are connected to 85 the superstructure B. Suitable guy wires 12 are also provided and are connected with the superstructure and masts or beams, these guy wires and brace bars or beams 11 serving to maintain the masts in rigid relation 90 with the superstructure and platform. A ladder indicated at 13 and extending from the platform to the upper tie 9 serves as means whereby access may readily be had to any portion of the machine above the 95 platform.

Suitably journaled in the superstructure B and extending longitudinally thereof and adjacent the lower ends of the vertical beams or masts 5, is a shaft 14. This shaft 100 has keyed upon it at its ends the smaller sprocket wheels 15. The latter it will be noted, are disposed beyond the ends of the superstructure. A second shaft 16 is journaled in parallel relation with the shaft 14, 105 near the upper ends of the masts or beams 5. Shaft 16 is carried in bearings having adjusting mechanisms indicated at 17, whereby said shaft may be adjusted relatively to the shaft 14. Keyed on the shaft 110

16 at the ends thereof are the larger sprocket wheels 18. It will be noted that the shaft 16 is disposed on the outside of the plane of the masts, while the shaft 14 is disposed on the inside of that plane.

Each of the pairs of sprocket wheels 15 and 18 carries an endless conveyer chain 19. These chains 19 run in unison by reason of the fact that the sprocket wheels carrying them are fastened to their respective shafts, the latter being journaled for rotation.

Each of the chains 19 has pivoted thereto and on the outer face thereof at equi-spaced intervals, a plurality of bars or plates 20.

The latter are pivotally connected to the chains at points above or adjacent their centers through the medium of ears 21 formed on or secured to suitable links of the chain. Extending outwardly from each of the bars

20 is an arm 22. A brace 23 connects the outer end of each arm with the lower end of the bar to which that arm is attached. These arms 22 are arranged at a slight angle with respect to the plates or bars 20, and

25 they extend outwardly from the chains, so that as indicated in Fig. 2, the arms on the descending flight of the conveyer, or that flight nearest the lumber pile indicated at 24, extend toward the lumber pile and are

30 inclined slightly upwardly. It will be noted that by reason of the shafts 14 and 16 being disposed on opposite sides of the plane of the beams or masts, that the conveyer is disposed at a slight angle, whereby the upper end of the conveyer is adjacent the lumber pile while the lower end thereof is spaced from said lumber pile.

Referring more particularly to Fig. 3, it will be noted that the shaft 14 is provided 40 with a friction pulley 25 over which a flexible brake band 26 provided with a segmental brake shoe 27 extends. The outer end of the band is fastened as at 28 to one of the members of the superstructure B, and 45 the inner end of said band 26 is connected by a link 29 with a brake lever 30. The latter is hingedly connected as at 31 to another member of the superstructure B. The outer end of the brake lever 30 is connected 50 by an adjustable link 32 with an arm 33 carried by a rock shaft 34. The latter is journaled for reciprocation in suitable brackets 35 secured to the platform (see Fig. 2). Near its outer end the brake lever is 55 provided with a depending weight 36 which normally maintains the brake shoe in engagement with the friction pulley 25. The ends of the rock shaft 34 are bent at right angles to form the arms or levers 37. The latter it will be noted extend in a direction 60 opposite to the direction in which the lever 33 extends. Pedals 38 are provided on the outer ends of the arms 37, and may be depressed by the foot of the operator. Such 65 depression will rock the shaft 34 in such

manner as to raise the brake lever 30, and hence relieve the tension on the friction pulley 25, thus allowing the shaft 14 to rotate.

Extending outwardly from the superstructure D and on the same side thereof as 70 that on which the shaft 16 is disposed, is a platform 39. The latter is provided with rollers 40 at its ends, said rollers being journaled transversely of the platform and in substantial parallel relation with the conveyer arms 22. The platform 39 is of a length less than the distance between the chains 19, so that as the latter rotate, the arms 22 may pass below the platform 39 75 near the ends thereof and outside of said platform.

The brake mechanism may be provided as shown in Fig. 1, with a cowl or housing 41, in the form of a curved shield.

The operation of the device may be briefly 85 described as follows: When it is desired to unload lumber from the top of any given stack, the device is moved by hand to take a position alongside the lumber stack with the upper flight of the conveyer disposed 90 near that stack. The lumber is then removed from the stack and placed upon the arms 22 carried by the descending flight of the conveyer, and the weight of the lumber moves the conveyer in such direction that the lumber is lowered and is finally disposed upon the rollers 40, from which it may be readily withdrawn by the operator. During the time that the lumber is descending, the brake is adapted to be controlled by the 100 operator for regulating the rate of descent of the lumber, and for stopping it at will. The brake it will be noted, is ordinarily on, and in order that the lumber may descend, the operator must necessarily depress the 105 pedal 38 so as to release the brake. Thus, the gravity actuated conveyer is at all times under the control of the operator, and danger of the operator being struck accidentally by descending lumber is reduced to a minimum.

It will be noted that most of the weight of the device is placed upon one side of the platform, and in order to equalize this weight, the opposite side of the superstructure is provided with a pair of weight boxes 115 42 in which suitable weights may be placed so that the strain and weight upon the ground wheels and platform will be equalized.

Although I have described the preferred embodiment of my invention, I may desire to make such changes in the construction, combination, and arrangement of parts thereof, as do not depart from the spirit of 125 the invention and the scope of the appended claims.

I claim:—

1. A device of the class described comprising a portable platform, a superstruc- 130

- ture mounted thereupon, vertically extending masts disposed in spaced relation and carried upon the platform, means for bracing the masts, a pair of shafts journaled on opposite sides of the plane of the masts and adjacent the lower and upper ends respectively thereof, small sprocket wheels keyed upon the lower shafts, larger sprocket wheels keyed upon the upper shaft, conveyor chains carried by each of the pairs of larger and smaller sprocket wheels, a plurality of bars pivotally connected at spaced intervals to each of the conveyor chains, arms extending outwardly from said bars, braces connecting the arms and bars, said arms being disposed at a slight upward inclination with respect to the descending flight of the conveyor, said arms adapted to have material placed upon them whereby the material may be lowered through the action of gravity, brake means for controlling the movements of the conveyor, a platform carried by the superstructure and provided with rollers, said arms adapted to pass said platform while descending, and means carried by the superstructure for counterbalancing the weight of the mechanism mounted thereupon.
2. A device of the class described comprising a portable platform, a pair of vertically extending masts disposed in spaced relation on said platform, a superstructure to which the masts are braced, an endless conveyor carried by the masts and being disposed in a plane at an inclination to the plane in which the masts lie, outwardly extending arms pivotally connected to the conveyor and adapted to receive lumber whereby the latter may be lowered by gravity, means for automatically receiving the lumber from the said arms, and means for counterbalancing the weight of the mechanism mounted on said platform.
